BATTERY CONNECTER

Fred H. Rabe, Pittsburgh, Pa.

Application November 4, 1931, Serial No. 572,942

7 Claims. (Cl. 173—259)

The present invention relates broadly to the art of electrical conductors, and more particularly to conductors of such character adapted to be utilized as detachable connectors for storage batteries and the like.

At the present time it is customary, more especially with storage batteries as utilized for automotive purposes, to provide the same either with substantially cylindrical or substantially truncated cone shaped posts to which the desired terminals of the respective circuits are connected. The connection is customarily made through the medium of a deformable clamp employing a bolt or the like for drawing the parts of the clamp into firm electrical contact about the post. Due to the corrosive action to which the parts are subjected, ready removal of the terminals from the battery is made difficult.

The present invention has for one of its objects 20 the provision of a quickly detachable connector embodying spring pressed parts which are effectively held in yielding engagement about a battery post in such manner that application and removal of the connector is facilitated.

Another object of the invention is to provide a 25 detachable connector of the character referred to of comparatively rigid and compact construction comprising a minimum number of parts and with the parts so disposed that those particularly 30 susceptible to corrosion are substantially enclosed or housed.

In the accompanying drawing I have shown for 35 purpose of illustration only, a preferred embodiment of the invention. In the drawing:

Figure 1 is a perspective view of a portion of a battery having a connector constructed in accordance with the present invention in cooperative relation thereto;

Figure 2 is a horizontal sectional view through 40 the connector of Figure 1 showing the position of the parts when removed from a battery post;

Figure 3 is an end elevational view of the connector illustrated in Figure 2 looking at the left hand end thereof as viewed in Figure 2;

Figure 4 is a side elevational view of the connector of Figure 2; and

Figure 5 is a longitudinal sectional view along the line V—V of Figure 2 looking in the direction of the arrows.

In accordance with the present invention, there is provided a connector particularly adapted for use with the terminal posts 2 of suitable storage batteries 3, although the utility of the invention is not thus limited. Such a connector preferably 55 comprises a terminal member 4 and a swinging

clamp 5 having a pivotal connection 6 with the terminal member. The terminal member is provided on one side thereof with a substantially semi-circular bearing portion 7 adapted to surround substantially one-half of a battery post, the 60 clamp 5 comprising a substantially semi-circular portion 8, the two portions when in the position illustrated in Figures 1 and 2 being adapted to substantially completely embrace and surround 65 the battery post with which connection is to be made.

In order to make the structure as compact as possible, the meeting plane 9—9 between the portions 7 and 8 preferably not only extends through the pivot 6, but at an angle to the longitudinal axis of the terminal member 4, thereby 70 enabling the pivot 6 to be located closely adjacent the cable axis.

The terminal member 4, which is conveniently 75 in the form of a casting of lead, copper, or other suitable conducting material, is formed with a recess 10 adapted to receive one end of a cable 11. Extending in line with the recess 10 is a second recess 12 forming a housing for 80 a compression spring 14. The recesses 10 and 12 are herein illustrated as being separated by a partition or diaphragm 15 having a centering projection 16 thereon for one end of the spring 14. The opposite end of the spring is adapted to 85 surround a centering projection 17 on the handle portion 18 of the swinging clamp 5. The projection 17 is herein illustrated as being carried by a substantially circular enlargement 19 on the handle portion of the clamp, the outer diameter of the portion 19 being such as to form 90 an approximate closure for the end of the recess 12. Adjacent its outer end, this last mentioned recess is provided with a slot 20 through which 95 a relatively narrow portion 21 of the clamp handle is adapted to move, the slot being on the 100 post engaging portions 7 and 8.

Projecting laterally from the member 4 is a lug 22 providing a substantially flat face 23 in 105 opposed substantially parallel relationship to the outer face of the handle 18, thereby providing gripping extensions adapted to be engaged either between fingers or a suitable tool for enabling the clamp 5 to be swung in a counter-clockwise direction about its pivotal mounting point and thereby move the post engaging portions 7 and 8 outwardly one with respect to the other for 110 releasing the post 2.

To those skilled in the art it will be apparent that spring 14 will be so selected as to insure the 110

maintenance of the portions 7 and 8 in proper engagement with a battery post and the establishment of a proper electrical connection therebetween. This electrical connection is further insured by the provision of circumferentially extending ribs 24 and 25 formed respectively on the portions 7 and 8, thus providing localized contact zones adapted to more effectively bite into the battery post and thus not only insure a good electrical connection therebetween, but also minimize the possibility of loosening of this connection. This is particularly desirable in the case of tapered posts as herein illustrated, although the invention is equally applicable in connection with substantially cylindrical posts.

From the foregoing description, it will be apparent that I have provided a detachable connector comprising but two body members, one of which not only forms a terminal connector, 20 but a housing for an actuating spring, and the other of which forms a clamp and cover for the housing. Inasmuch as the construction is such that substantially half of the post is embraced by the portion 7 of the connector, an effective 25 current carrying path of short length from the post to the cable 11 is provided. The location of the pivotal connection 6, made possible by reason of the angular meeting plane of the portions 7 and 8, precludes the use of relatively long 30 lugs or brackets forming a mounting for the pivot pin itself.

Further advantages arise from the provision of a terminal member of such structure as to provide a cable receiving recess and spring housing 35 therein in substantially axial alignment, thus reducing the over-all diameter of this member.

Further advantages arise from the provision of an actuating spring having its effective axis angularly disposed relatively to the meeting 40 plane between the post engaging clamps whereby the post itself cooperates with the spring in maintaining the clamping portions in the desired relationship to the post.

While I have herein illustrated and described 45 the preferred form of my invention, it will be understood that changes in the construction, contour and relationship of the parts may be made without departing either from the spirit of my invention or the scope of my broader 50 claims.

I claim:

1. A detachable connector for batteries, including a terminal member having a recess therein, a lug projecting from said member, a spring housed within said recess, a swinging clamp pivotally connected to said member and normally urged into clamping engagement therewith by said spring, said clamp having a handle portion projecting therefrom in opposed relationship to 55 said lug and forming with said lug compressing means for said spring.

2. A detachable connector for batteries, including a terminal member having a recess therein, a lug projecting from said member, a spring housed within said recess, a swinging clamp pivotally connected to said member and normally urged into clamping engagement therewith by said spring, said clamp having a handle portion projecting therefrom in opposed relationship to 60 said lug and forming with said lug compressing means for said spring.

70

compressing means for said spring, said clamp further forming a closure for said spring recess.

3. A detachable connector for batteries comprising a split member with the portions pivoted to each other, said portions together defining a cylindrical opening adapted to receive a battery post, one portion of said split member having an enlargement recessed to receive a cable end and recessed to house a spring, and a spring therein for urging the portions of the member into clamping engagement with the opposite sides of the post, the recess housing the spring being adjacent the pivot between said portions and the cable recess being remote from said pivot.

4. A detachable connector for batteries, including a terminal member having a recess for permitting a battery post to be partially set into said member, a swinging clamp pivotally connected to said member, a cable connected to said member on the opposite side of said recess from the pivot of said clamp, and a coil spring for normally urging the clamp into engagement with the opposite side of the post from said member, said member having a cylindrical recess therein housing said spring and conforming substantially to the over-all dimensions of the spring, and said clamp forming a closure for one end of said spring recess.

5. A detachable connector for batteries, including a terminal member having a cable receiving recess in one end thereof, a spring receiving recess in the opposite end thereof, said recesses being cylindrical and in substantially axial alignment, a post receiving recess for permitting a battery post to be partially set into said member, a compression spring in said spring recess, and a swinging clamp pivotally connected to said member with the axis of the pivot on the opposite side of the post recess from the cable recess, said clamp being normally urged pivotally into clamp- 115 ing engagement with the opposite side of the post from said member by said spring.

6. A detachable connector for batteries, including a terminal member having a cable receiving recess, a spring receiving recess, a post receiving 120 recess for permitting a battery post to be partially set into said member, a compression spring in said spring recess, and a swinging clamp pivotally connected to said member with the axis of the pivot on the opposite side of the post recess from the cable recess, said clamp being normally urged into clamping engagement with the opposite side of the post from said member by said spring, said clamp having a portion overlying the end of said spring recess and engaged by said compression spring.

7. A detachable connector for batteries, including a terminal member having a recess for receiving one side of a battery post, a swinging clamp having a contact portion for engaging the other side of the post, a cable connected to said member on the opposite side of said recess from the pivot of said clamp, a cylindrical recess in said terminal member on an axis angularly related to the meeting plane of the terminal member and swinging clamp, and a compression spring housed within said cylindrical recess for normally urging the clamp into engagement with the post.

FRED H. RABE. 145
